MACHINE GUN

Leopoldo A. Carrillo, Big Wells, Tex.

Application January 16, 1934, Serial No. 706,883

5 Claims. (Cl. 89—13)

This invention relates to improvements in machine guns and has as its object the provision of such a gun that is adapted chiefly for air crafts and armor piercing purposes, provision being made for the discharge of a plurality of bullets or cartridges at each firing of the gun.

The invention together with its numerous objects and advantages will be best understood from a study of the following description, taken in connection with the accompanying drawings wherein:

Figure 1 is a side elevational view of the gun.

Figure 2 is an enlarged fragmentary elevational view of a portion of the gun showing the position of the parts when ready for firing of the gun.

Figure 3 is an enlarged side elevational view of a magazine disk with the cartridge cylinders in position thereon.

Figure 4 is a side elevational view of the disk with the cartridge cylinders removed.

Figure 5 is a view similar to Figure 4 of the opposite side of the magazine disk.

Figure 6 is an edge elevational view of the magazine disk.

Figures 7 and 10 are sectional views taken substantially on the line 7—7 and 10—10 respectively of Figure 3.

Figure 8 is an enlarged fragmentary view partly in section and partly in elevation showing the firing position of one of the cartridge cylinders on the magazine disk.

Figure 9 is a detail sectional view taken substantially on the line 9—9 of Figure 4.

Figure 11 is an enlarged fragmentary elevational view showing the manner of locking a cartridge cylinder on the magazine disk.

Figures 12 and 13 are sectional views taken substantially on the lines 12—12 and 13—13 respectively of Figure 11.

Figure 14 is a side elevational view of one of the cartridge carrying cylinders.

Figure 15 is an elevational view of the opposite side of the cartridge cylinder.

Figure 16 is an elevational view of one end of the cartridge cylinder.

Figure 17 is an elevational view of an opposite end of said cylinder.

Figure 18 is a sectional view taken substantially on the line 18—18 of Figure 15.

Figure 19 is a plan view of an ejector plate.

Figure 20 is an edge elevational view thereof.

Figure 21 is a plan view of a collar hereinafter more fully referred to.

Figure 22 is an edge elevational view of the collar.

Figure 23 is a perspective view of one of the bolts for the plate shown in Figure 19.

Figure 24 is an elevational view of a finger piece or handle for the bolt shown in Figure 23.

Figure 25 is an edge elevational view of the finger piece or handle referred to above.

Figure 26 is a perspective view of a sleeve hereinafter more fully referred to.

Figure 27 is a side elevational view of the gun proper with certain parts removed.

Figure 28 is a sectional view taken substantially on the line 28—28 of Figure 1.

Figure 29 is a plan view of a rotatable frame forming part of the gun mounting.

Figure 30 is a sectional view taken substantially on the line 30—30 of Figure 29.

Figure 31 is a side elevational view of a bar supported by the frame shown in Figure 29.

Figure 32 is an elevational view of the pedestal forming part of the gun mount.

Figure 33 is a fragmentary enlarged sectional view showing the manner of rotatably supporting the cylinder magazine disk.

Figure 34 is an elevational view of the supporting shaft for the aforementioned disk.

Figure 35 is a perspective view of the trigger.

Figure 36 is a sectional view through the spring motor.

Figures 37 and 38 are sectional views taken substantially on the lines 37—37 and 38—38 respectively of Figure 36.

Figure 39 is a plan view of a partition plate arranged between the springs of the aforementioned spring motor.

Figure 40 is an elevational view of one of the rack wheels forming part of the spring motor.

Figure 41 is a similar view of the other of the rack wheels forming part of said spring motor.

Figure 42 is a perspective view of a reinforcing bar.

Figure 43 is a plan view of the shaft of the spring motor.

Figure 44 is an elevational view of the bolt assembly of the gun.

Figure 45 is a side elevational view of the outer cylinder of said bolt assembly.

Figure 46 is an elevational view of the inner cylinder of said bolt assembly.

Figure 47 is an elevational view of the firing pin.

Figure 48 is an elevational view of the bolt shown in Figure 23.

Figure 49 is an end elevational view of the firing pin.

Figure 50 is a side view of the cap for the inner cylinder, certain parts of the cap being broken away and shown in section.

Figure 51 is a sectional view taken substantially on the line 51—51 of Figure 1.

Figure 52 is an elevational view of a spring pressed plunger assembly forming part of the trigger mechanism of the gun.

Figure 53 is an elevational view taken at right angles to Figure 52.

- Figure 54 is an elevational view of the cylinder of the said trigger assembly.
- Figure 55 is an edge elevational view of a disk forming part of said assembly.
- 5 Figure 56 is a plan view of said disk.
- Figure 57 is an elevational view of the plunger forming part of said assembly.
- Figure 58 is a sectional view taken through the bolt and trigger assembly.
- 10 Figures 59 and 60 are sectional views taken substantially on the line 59—59 and 60—60 respectively of Figure 58.
- Figure 61 is a plan view of a stop lug carried by the firing pin.
- 15 Figure 62 is a sectional view taken substantially on the line 62—62 of Figure 53.
- Referring to the drawings by reference numerals and to Figure 1 it will be seen that the gun indicated generally by the reference numeral 20 al 1 is mounted for rotative movement in a horizontal plane on a mount indicated generally by the reference numeral 2.
- In the present instance the mount 2 comprises a pedestal 3 that at its upper end, as clearly 25 shown in Figure 8, is provided with a pin 4 about which is revolute a hub 5 secured in place through the medium of a nut 6. The hub 5 has extending therefrom arms 7 that project upwardly and are integral with the sides of a frame 30 indicated generally by the reference numeral 8. For securing the frame 8 at the desired adjustment there is provided on the upper end of the pedestal 3 a flange 9 provided with a circular series of apertures and a flange 10 on the hub 35 5 that is apertured to register with a desired one of the apertures in the flange 9. For engagement with aligned apertures of the flanges 9 and 10 is a suitable pin 11 all of which is clearly shown in Figure 28.
- 40 Mounted transversely of the frame 8 at each end thereof is a pair of bolts 12 on which are slidably mounted grooved collars 13 that are resiliently held in centered position through the medium of coil springs 14. A bar shown in Figure 31 and indicated by the reference numeral 15 extends longitudinally of the frame 8 and is provided on its under side with notches 16 that engage the grooved collars 13 in a manner suggested in Figure 28. Between the ends thereof the bar 15 is provided with a diametrically enlarged portion 17 that fits within an aperture 18 provided in a brace structure 19 provided for the barrel of the gun as shown in Figure 7. On one end thereof the part 17 is provided with a collar 20 while the opposite end of the part 17 is threaded for reception of a nut 21 whereby the bar 15 is secured to the bracket 19 against lateral movement relative thereto as will be clear from a study of Figure 28.
- 50 It will thus be seen that with the gun mounted on the standard 3 the gun may be revolved to shoot in any desired direction.
- There is also provided for the barrel portion of the gun a brace bar 22 that has a forked end 65 straddling the post 3 and provided at said end with wing screws 23 operating in a circular groove 24 provided on the standard 3. At its upper end the brace bar 22 is secured as at 25 to a lug 26 provided at the under side of the barrel of the gun 70 adjacent the brace or bracket 19. Through the medium of the brace 22 the gun is secured against swinging relative to the bar 15 as an axis.
- In accordance with the present invention the gun comprises a barrel 25 connected with a breech 26 through the medium of an integral 75
- stock 27 and the rear end of the barrel is spaced from the breech 26 as clearly shown in Figure 27. Secured to the breech 26 is the stock 27 and the breech 26 is provided with a suitable trough for accommodating the bolt assembly of the gun. Bridging the breech-slot thus formed is a reinforcing bar 29.
- The bolt assembly comprises, as will be clear from a study of Figures 45 to 50 an outer cylinder 28 which slidably fits within the breech 26 and 10 is provided with the usual lever 29 that is engageable in a notch 30 provided on one side of the breech for holding the bolt in its forward position. The cylinder 28 is open at each end and has slidably mounted therein an inner cylinder 31 15 which is closed at its inner end, and is provided at its outer end with a cap 32 screw threadedly engaged therewith. At its closed end the bolt 31 is provided with an opening which accommodates the shank of the firing pin 33. Disposed on the 20 inner end of the shank of the firing pin is a coil spring 34 which at one end impinges against the closed end of the cylinder 31, and at its other end impinges against a washer and nut assembly 35 25 provided on the inner end of the shank of the firing pin 33. The firing pin 33 is also provided with an enlarged head 36 equipped on its free end face with a series of projections 37. The number of projections 37 correspond to the number of bores 38 provided in the gun barrel 25. In the present 30 instance I have shown the gun barrel as provided with ten bores 38 nine of which are arranged in a circular series and the tenth one of which is arranged centrally and axially of the barrel. The projections 37 are arranged on the end 36 of the 35 firing head in substantially the same manner as the bores 38 are arranged there being one projection 37 for each bore 38.
- For limiting movement of the firing pin 36 there is provided a lug 39 that is suitably secured to the 40 head 36 of the firing pin and operates in a slot 40 provided in the cylinder 28.
- As shown in Figure 58 the cylinder 31 of the bolt is provided with a cam like lug 41 that operates in a slot 42 also provided in the cylinder 28. 45 Cooperable with the lug 41 is a trigger mechanism that is suitably mounted in the breech of the gun and includes a cylinder 43 in which is slidably mounted a plunger 44 provided on its upper end with a cam like lug 45 complementary to the lug 41 50 and engageable therewith for holding the cylinder 31 in a retracted position. The plunger 44 is normally urged upwardly relative to the cylinder 43 through the medium of a coil spring 46 clearly shown in Figure 58. The trigger per se is indicated by the reference numeral 47 and is pivotally mounted as at 48. The trigger 47 has an end 49 that operates in a suitable slot provided in the cylinder 43 and in an aperture provided in the plunger 44 in a manner, when the trigger 47 is 60 pulled, to move the plunger 44 downwardly against the action of spring 46 to release the cylinder 31. As is apparent upon release of the cylinder 31 coil spring 34 will expand to forcibly move the cylinder 31 to the right in Figure 8 in a manner to forcibly 65 engage the head 36 of the firing pin to effect a firing of the gun. In loading the gun the cylinder 31 to the right in Figure 8 in a manner to forcibly spring 34 to engage the cam lugs 41, 45 as shown in Figure 8 to secure the gun in a "cocked" condition.
- The breech 26 is provided with a depending extension 50 between which and part 19a of the bracket 19 is supported a shaft 51 which latter has a threaded end screw threadedly engaged in 75

an aperture provided in the extension 50 and a second end extending through a suitable aperture provided in the bracket extension 19a, and at said end is equipped with suitable nut means 52 to secure the shaft in position. Revolubly mounted on the shaft 51 is what may be termed a revoluble magazine or disk 53 that is suitably apertured to accommodate the shaft 51 and is provided in said aperture with suitable bearings 54. As is clear the disk 53 operates in the breech slot between the barrel 25 and the breech 26 and is provided for successively bringing the cartridge cylinders 55 carried by said disk into position alining with the barrel 25 and the cylinder 28 of the bolt, thus loading the gun.

In the present instance the disk 53 is provided on its periphery with a circular series of arcuate or semi-circular recesses or pockets 56 for accommodating the cartridge holders or cylinders 55. Extending inwardly from each recess 56 is a restricted slot 57 that connects the recess 56 with a substantially circular groove 28 one end of which is partially closed by an integral lug 59. A retaining pin for each cartridge holder 55 is also provided and the same consists of a bolt 60 that has the headed end thereof engaged with an aperture in the lug 59, and this bolt 60 extends longitudinally of the groove 58 as shown in Figure 9. On the bolt 60 is an elongated sleeve 61 and disposed about the sleeve 61 is a coil spring 62 that at one end bears against the slideable collar 63 engaged with the sleeve 61 and yieldably retains the collar 63 against the inner side of the lug 59 as also shown in Figure 9. The collar 63 as shown in Figures 8, 21 and 22 is provided with an integral shank or projection 64 will operate in the slot 57 and serve to retain the collar 63 against rotative movement.

On that side thereof opposite to the lugs 59 the disk 53 is provided with a circular groove 65 which accommodates a retaining ring 66 that is suitably apertured for receiving the threaded ends of the bolts 60. It will thus be seen that the springs 62 are confined on the sleeves 61 between the collars 63 and the ring 66, and the ring 66 is retained on the bolts 60 between nuts 67, threadedly engaged with the bolts and the adjacent ends of the sleeves 61 as will be clear from a study of Figure 9.

Each of the cartridge holders or cylinders 55 comprises a circular or cylindrical body having a series of bores 68 provided therein and arranged to correspond with the arrangement of the bores 38 of the barrel of the gun. The bores 68 are adapted to accommodate the cartridges 69 in a manner suggested in Figure 10 wherein it will be seen that the tips of the cartridges project beyond one end of the holder 55 and the flanged heads of the cartridges project beyond the opposite end of the holder 55.

Each holder 55 is adapted to be accommodated within a recess 56 on the disk 53 and is provided on its periphery with ribs 70 engageable in grooves provided by T-headed ribs 71 provided on the periphery of the disk 53 as shown in Figure 4 whereby provision is made for securing each holder 55 in proper position within its recess 56. Also, at one end thereof each holder 55 is provided with a radial projection 72 that is provided with a suitable head 73 adapted to engage the sleeve 61 in the manner shown in Figure 8. It will thus be seen that in placing a holder 55 on a disk 53 the holder 55 is introduced into its recess 56 laterally from one side of the disk, namely the side of the disk equipped with the lug 59. As shown in Figure 8 in the placing of the holder

55 on the disk 53 the shank 72 associated therewith will be accommodated in the slot 57 while the head 73 of the shank will clear the lug 59 and move into the groove 58 to engage about the sleeve 51 as also shown in Figure 8. The manner of engaging the holder 55 with the disk 53 and within its seat 56 will be clear from the above when considered in conjunction with Figure 8.

When all of the holders 55 have been placed on the disk 53 there is applied to the disk 53 on the sides thereof equipped with the lugs 59 an ejector plate 74 that is accommodated in a suitable recess provided in said side of the disk 53. This plate 74 at its edges is suitably notched as at 75 and is also suitably provided centrally thereof as 15 at 76 to engage behind the flanges of the head of the cartridges 69 in a manner suggested in Figures 3 and 10 so that upon movement of the plate 74 away from the holder 55, or to the dotted line position shown in Figure 10 an ejection of all the 20 empty shells will be easily effected.

The disk 74 is provided at opposite sides thereof with apertured lugs with which are engaged elongated bolts 77 that are accommodated in grooves 78 provided on the periphery of the holder 55. 25 Screw threaded on the free ends of the bolts 77 are handle or finger pieces 80 whereby the bolts 77 and the plates 74, screw threadedly engaged with the bolts, may be moved to the position shown in Figure 10 for ejecting the cartridges. The plate 30 74 is normally urged into engagement with the holder 55 through the medium of coil springs 79 disposed about the bolts 77 within the grooves 78 and bearing at one end against the handle pieces 80. Straps 81 are provided at one end of the 35 slots 78 and the handle pieces 80 are normally engaged with the straps through the medium of the coil springs 79 as also will be clear from a study of Figure 10.

For locking the individual holders 55 on the disk 40 53 there is provided on the disk, on one side thereof, for each of the holders 55 a latch which includes a casing 82, a spring pressed bolt 83 projectable outwardly of the casing and a keeper 84 aligned with a bolt casing and with which the bolt 45 83 is engageable as shown in Figures 11 and 12. These latch devices are mounted so that the bolts 83 thereof bridge the slots 57 and as shown in Figure 2 the projections 72 of the members 55 bear against the bolts 83. For revolving the disk 50 53 to successively bring the cylinders 55 carrying the charge into position for firing purposes there is provided a spring motor indicated generally by the reference numeral 85. The spring motor 85 is mounted beneath the breech 26 and includes 55 as clearly shown in Figures 1 and 36 to 41 inclusive a two-part casing 86 secured together by bolts 87 and between the meeting ends of the sections of the casing is arranged a partition disk 88. Provided in the ends of the casing are bearings and journaled within these bearings are elongated hubs 90, 91, and with which are integral ratchet wheels 92, 93. A shaft 94 has a diametrically enlarged end journaled in a bracket extension 50a depending from the breech 26 and 60 the other end journaled in the hub of the ratchet wheel 93 as shown in Figure 36. This ratchet wheel 93 has a hub extension 95 that is journaled in a bracket extension 50b that also extends 65 downwardly from the breech 26 opposite the extension 50a. 70

Mounted in the casing 86 at opposite sides of the partition 88 are springs 96 which at one end are suitably secured to the hubs 90, 91 and at an opposite end secured to the casing 86. To pre- 75

vent retrograde movement dogs 97 are pivotally mounted on the bracket extensions 50a, 50b and engage the ratchet wheels 92, 93 as shown in Figure 36. For rotating the casing 86 to wind the springs 96 there is provided a suitable handle 98 that has screw threaded engagement with the hub extension 95 of the ratchet wheel 93 as also shown in Figure 36.

On the enlarged end thereof the shaft 94 is provided with a gear 99 that is in mesh with a gear 100 which is secured to one side of the disk 53 through the medium of bolts 101 as shown in Figure 33. It will thus be seen that upon operation of the spring motor drive will be transmitted therefrom through the gearing 99 and 100 to the disk 53 for revolving the disk to bring the cartridge holders 55 successively into alignment with the barrel of the gun.

To prevent further rotation of the disk 53 when a cartridge carrier 55 is brought into proper position with respect to the barrel of the gun there is provided on the rear end of the barrel an arcuate flange 102 with which the projecting ends of the bullets will engage when the proper holder 55 comes into alignment with the barrel thus preventing further rotation of the disk 53. To accommodate the flange 102 each holder 55 at its forward end is formed to provide a groove 103 into which flange 102 is received when the carrier is moved forward as will hereinafter appear in the operating of the gun.

In operating the gun it will be apparent that when a holder 55 is brought into alignment with the barrel of the gun, by properly manipulating the lever 29 the cylinder 28 is moved forwardly and by engaging the lever 29 in the notch 30 is held in forward position. Upon movement of the cylinders 28 forwardly the front end thereof will engage the holder 55 moving the holder forwardly from the position shown in Figure 1 to the position suggested in Figure 2 so that the ends of the cartridges will pass into the bores of the barrel.

The trigger mechanism and the parts of the bolt are then in the position shown in Figure 8. Obviously by pulling on the trigger 27 to move the plunger 44 thereof downwardly cylinder 31 of the bolt is released and under action of spring 34 will move forwardly or to the right in Figure 8 to forcibly contact the head 36 of the firing pin 35 causing said head 36 to move forwardly and project beyond the forward end of the cylinder 28 for bringing the protuberances 37 on the firing pin into forcible contact with the cartridges resulting in a discharge of the gun.

When the gun has been thus fired the cylinder 28 of the bolt is retracted whereupon the holder 55 within the breech-slot of the gun will move to the position shown in Figure 1 under the action of the spring 62 so that the disk 53 is then free to 60 revolve in a clockwise direction for bringing the next successive holder 55 into position in alignment with the barrel of the gun for subsequent firing thereof.

It will be apparent that during the operation of the gun loading of the disks 33 can be accomplished by removing the cylinders 55 whose charges have been fired and replacing them with properly charged cylinders.

It will also be apparent that an emptying of a holder 55 of the empty shells can be readily accomplished by manipulating the handles 80 to effect sliding of the same toward the left in Figure

10 to move the plate 74 toward the dotted line position suggested in said figure to eject the shells.

Having thus described my invention, what I claim as new is:

1. In a gun of the class described, a revolvably mounted magazine disk provided on its periphery with a series of arcuate recesses, a groove inwardly from each of the recesses and a slot connecting each groove with its recess, and cartridge holders arranged within said recesses, each cartridge holder being provided with a projection extending into said slot; and an enlarged head on said projection extending into the groove for holding the cartridge holder in position on the magazine disk.

2. In a machine gun, and in combination, a revolvably magazine provided with a recess in its periphery, a groove inwardly from said recess, and a slot connecting the groove and recess, an integral lug at one end of the groove, a bolt connected at one end with the lug and extending longitudinally of the groove, a spring disposed about said bolt, a cylindrical cartridge holder adapted to fit within said recess and provided with a projection operating in said slot, said projection having an arcuate head straddling the bolt within the groove, means at one end of the magazine and extending across the adjacent end of the groove to prevent displacement of the cartridge holder laterally at one side of the magazine, and latch means at the opposite end of the magazine and including a bolt projectable across said slot and against which the projection on the cartridge holder is engaged for securing the holder on the magazine against lateral displacement.

3. In a machine gun, a revolvble magazine provided on its periphery with a circular series of relatively spaced grooves, and a series of cylindrical cartridge holders carried by the disk, each cartridge holder being provided on its periphery with a projection slidably fitting in a groove in the magazine disk.

4. A cartridge holder of the character described comprising a cylindrical body having a series of bores for accommodating the cartridges, an ejector plate at one end of the holder having notched portions engageable with the flanged heads of the cartridges for ejecting the shells upon movement of the plate in a direction away from the holder, and spring devices engaged with the plate and the holder for releasably retaining the plate in contact with one end of the holder with the notches of the plate engaging the said flanged heads of the cartridge shells.

5. A cartridge holder comprising a substantially cylindrical body provided with a plurality of bores to accommodate the cartridges, said holder being provided in the periphery thereof with a series of grooves, an ejector plate provided with a plurality of notched portions engaging the flanged heads of the cartridge shells for ejecting the shells of exploded cartridges, said plate being also provided with lugs, bolts extending through the lugs and into the grooves of the cartridge holder, said bolts having threaded ends screwed into the lugs on the plate, handle members on the free ends of the bolts operating in the grooves of the cartridge holder, and springs disposed about the bolts within the grooves and bearing on the handle pieces for normally urging the bolts inwardly of the grooves and the plate in contact with an end of the cartridge holder.

LEOPOLDO A. CARRILLO.
